UNITED STATES PATENT OFFICE.

FERDINAND POLL MILLER, OF EDDYVILLE, IOWA.

WASHING-MACHINE.

SPECIFICATION forming part of Letters Patent No. 274,140, dated March 20, 1883.

Application filed May 31, 1882. (Model.)

To all whom it may concern:

Be it known that I, FERDINAND POLL MILLER, of Eddyville, in the county of Wapello and State of Iowa, have invented a new and Improved Washing-Machine, of which the following is a full, clear, and exact description.

This invention relates to a cylindrical rubber with ribbed surface, arranged on journals in a wash-tub, together with a stationary concave rubber of ribbed or roller surface, located beneath the cylindrical rubber, together with apparatus for working the cylindrical rubber forward and backward, and so as to gain a little one way until the clothes are nearly passed through between the two rubbers, and then gain similarly in the other direction to work the clothes back again, the said apparatus being operated by means of a fly-wheel to which the power is applied by hand or foot, if preferred, as hereinafter described.

Reference is to be had to the accompanying drawings, forming part of this specification, in which similar letters of reference indicate corresponding parts in all the figures.

Figure 1 is a side elevation of my improved washing-machine. Fig. 2 is a plan view; and Fig. 3 is a longitudinal sectional elevation of the tub and the rubbing device.

A represents a rectangular tub, of wood, set upon legs B, and a sheet-metal bottom, c, with a concave part, D, midway between the ends of the tub.

E represent a series of small rollers, arranged side by side, with their ends pivoted in the housings F, forming a stationary concave rubber, said rollers being in a curved line a little above the concave part D of the bottom of the tub, with a concave perforated plate of thin sheet metal, G, located between them and said bottom D and attached to the lower edges of housings F.

H represents the fluted or ribbed cylindrical rubber, located over the stationary rubber and concentrically to it, being mounted on journals I, J, that have bearings in deep notches in the sides the tub, in which caps K are fitted over the journals, said caps being fastened by screws, to be removable to allow the rubber to be removed from time to time for cleaning the machine and for repairs.

The housings F are suspended by rods L and

springs M from bearers N, attached to the sides of the tub, over the journals of the cylindrical rubber and inside of said tub, for pressing the stationary rubber upward to cause the required pressure of the clothes between the two rubbers. The stud-pins P, attached to the sides of the tub and projecting through slots in the housings, are to prevent said housings and stationary rubber from being shifted sidewise under the action of rubber H.

The bearers N are detachably connected to the sides of the tub by screws O, to allow of the removal of the rubbers when required.

The perforated plate G forms a connection of housings F that is required for keeping the rollers E in their bearings in said housings when removed from the tub, and it also forms a guard to prevent the clothes from getting under the rollers. The perforations allow free circulation of the water. To enable the rubber H to be oscillated for rubbing the clothes, it is provided with a ratchet-wheel, Q, upon one of its journals projecting out of one side of the tub, to which a pawl, R, is applied for turning it to the right, said pawl being jointed to a bar, S, that is pivoted on the journal J. There is also a pawl, T, applied to said ratchet for turning it to the left, said pawl being jointed to a bar, U, that is also pivoted on the journal J of the rubber H. These pawls are connected by rods W to the rock-lever X, on opposite sides of its pivot Y, so that when one pawl advances the other retreats with respect to the ratchet. The rock-lever X is connected by a rod with the crank pin b of the fly-wheel d, to which the power is applied for working the rubber H.

The rock-lever X has a slot, e, for its pivot Y, and said lever X has a shifting-bar, f, connected with it for shifting along on pivot Y to one side or the other of the center between rods W, for shortening the throw of one of the pawls R, T and lengthening the throw of the other, according to which way it is desired that the rubber H shall have the greatest movement to cause the clothes to gain in one direction, although the rubber H works forward and backward, the object being to have the clothes enter between the rollers at one side and gradually work through or nearly through to the other side, then back again, and repeating as many times as desired, the changes being effected simply by shifting the rock-le-

ver on its pivot Y first one way and then the other; or the pivot may be arranged to shift along the lever.

The lever *f*, by which rock-lever *X* is shifted, 5 is pivoted to the sides of the tub at *g*, with its handle ranging above the top of the tub, where it is provided with a latch, *i*, and a catch, *j*, for setting it in three different positions—viz., right, left, and middle—according as it is desired to have the rubber *H* work. The connection of lever *f* with the vibrating lever *X* is by means of a clip, *k*, pivoted to lever *f* at *l*, and sliding up and down on the cleat *m*, attached to lever *f*; but the connection may be 15 made in various ways.

The pawls *R* and *T* are pivoted to their respective bars *S* and *U* at *n*, and they have a stud-pin, *p*, in the side working in a slot, *q*, in said bars to form stops to limit the vibration 20 of the pawls on the said bars. The bars *S* and *U* extend from journal *J* opposite to the pawls, and have a spring, *t*, bearing against their ends, which are suitably curved for working against said springs, the object being to hold the 25 bars *S* and *T* by the friction of the springs on them, so that at each reverse of the motion of the pawls said pawls will vibrate on the pivots *n* to lift the retreating pawl out of the ratchet and depress the advancing one into it, so that 30 when one pawl has greater throw than the other it will advance the ratchet more than said other pawl retreats. The bar *S* has a foot-lever, *u*, connected to it by a wire, *x*, by which to hold pawl *R* out of action altogether for a 35 short time whenever it may be desired to work the rubber *H* one way only for quickly enter-

ing the clothes to begin with or for discharging them quickly from between the rubbers.

Having thus fully described my invention, what I claim as new, and desire to secure by Letters Patent, is—

1. The combination, with vertically-slotted concave and bearers *N*, of the rods *L*, springs *M*, tub having the side studs, *P*, and the slotted housings, whereby the rubber is allowed a slight vertical spring movement without shifting laterally the housings or stationary rubber, as described. 45

2. The combination, with ratchet *Q* and rubber *H*, of right and left pawls, *R* *T*, bars *S* *U*, rock-lever *X*, and springs *t*, said pawls and bars being pivoted together, and said springs acting on said bars, substantially as described. 50

3. The rock-lever *X*, having a shifting fulcrum, right and left pawls, *R* *T*, jointed connecting-bars *S* *U*, and the friction-springs *t*, combined with ratchet *Q*, substantially as described. 55

4. The combination of shifting-lever *f*, clip *k*, and cleat *m*, with shifting rock-lever *X*, substantially as described. 60

5. A right and left handed ratchet mechanism consisting of ratchet *Q*, right and left pawls, *R* *T*, and jointed connecting-bars *S* *U*, one of said bars connected to a foot-lever for disconnecting one of said pawls, substantially as described. 65

FERDINAND POLLMILLER.
